PLAYER ACTION COMPANY, OF WORCESTER, MASSACHUSETTS, A CORPORATION
OF MASSACHUSETTS.

MUSIC-SHEET-GUIDING DEVICE.

1,246,865.

Specification of Letters Patent. Patented Nov. 20, 1917.

Application filed August 6, 1914. Serial No. 855,528.

To all whom it may concern:

Be it known that I, THEODORE P. BROWN, a citizen of the United States, residing at Worcester, in the county of Worcester and 5 Commonwealth of Massachusetts, have invented a new and useful Improvement in Music-Sheet-Guiding Devices, of which the following, taken in connection with the accompanying drawings, is a specification.

10 The present invention relates to music sheet guiding devices such as are used in automatic musical instruments to maintain the correct registration of the perforations of the music or note sheet with the corresponding apertures in the tracker-bar of the instrument.

An object of the invention is to provide a device of the above character which is simpler in construction, cheaper, and more durable than existing devices designed to accomplish the same results.

20 A further object is to provide a device of the above character which is capable of application to the mechanism of any of the 25 existing types of automatic musical instruments or piano players, without the necessity for a reorganization of the parts of the latter.

More specifically, a still further object is 30 to utilize instrumentalities already present in the player to which the device is applied, in order to provide in part for the actuation of the device, thereby greatly reducing the number of parts required.

35 Other and further objects will be apparent from the following description and the claim annexed thereto, reference being had to the accompanying drawings, in which—

Figure 1 is a front elevation of improved 40 guiding device which embodies my invention, and

Fig. 2 is a section on the line 2—2, Fig. 1.

Like reference characters refer to like parts in both figures.

45 The reference numerals 1 and 2 designate the frame members usually provided in automatic musical instruments for the support of the music spools 3 and 4 and the intermediate perforated tracker-bar 5. The spool 50 3, upon which the note sheet is drawn in the operation of the instrument, is permanently journaled in the said frames, being provided with the usual means, not shown, for insuring its rotative movement. The

note sheets are supplied permanently attached to spools 4, for insertion in the instrument when desired, and to this end the frame member 1 carries a longitudinally movable shaft 6, the outer reduced end of which is extended through a bracket 7 on the outside of said frame. A spring 8 surrounding said shaft, and disposed between the bracket 7 and a shoulder 9 on said shaft, operates to yieldingly maintain the inner end of said shaft toward the right in Fig. 1. The heads of each spool 4 are recessed to receive the inner end of shaft 6, and the inner end of an axially aligned shaft 10, carried by the other frame member 2, whereby to provide for the rotative mounting of said spool. The insertion of each spool 4 is effected by the depression of the shaft 6 against the resistance of spring 8, in the usual manner, in order to permit the registration of the recess in the other end of said spool with the inner end of shaft 10. When the spool is in position, the force of spring 8 yieldingly maintains the spool in centered position with respect to the shafts 6 and 10.

The shaft 10 has a reduced portion which 80 passes through a suitable bearing 11 carried by frame member 2, and is capable of longitudinal movement therein for a purpose hereinafter set forth. The tracker-bar 5, in addition to the note apertures 12, over 85 which the registering apertures of the note sheet are drawn as the latter is reeled onto the spool 3 from the spool 4 in the usual manner, has near one end an aperture 13, which communicates, by means of a tube 14, with the interior of an actuating pneumatic 90 15. The latter may conveniently be secured to or supported by a portion of the stationary framework which embodies the members 1 and 2, as illustrated in Fig. 1. The 95 interior of said pneumatic has formed therein a recess 16 from which a restricted aperture or bleed port 17 leads to a passage 18 which communicates with an exhausting device, not shown. The recess 16 is covered by a screen 19, of felt or other porous material, so as to permit the passage of air therethrough, but to provide an extended straining surface for said air to prevent the stoppage of the bleed port by fragments of paper, lint, or the like. The movable wall 20 of said pneumatic 15 has secured thereto a member 21 having a curved arm 22 against

which the outer end of shaft 10 is constantly pressed by the expansive force of spring 8. The face of said arm against which the shaft 10 bears is inclined from the vertical 5 in the direction of its length, as shown at 23. Consequently, the downward movement of said arm, by the collapsing of wall 20, effects movement of shaft 10 and spool 4 to the left, in Fig. 2, against the yielding resistance 10 of spring 8; while the expansive force of said spring operates to maintain the spool 4 and shaft 10 to the right, in Fig. 1, when the conditions tending to collapse said wall 20 do not exist.

15 The operation of my improved device is as follows:—When the automatic musical instrument is in operation, air is drawn through the interior of the pneumatic 15 by means of its connection through the bleed 20 port 17 with the before mentioned exhausting device. The aperture 13 is so disposed that in the normal position of the note sheet, *i. e.*, in the position where the perforations therein register accurately with the corresponding note apertures 12, only a portion 25 of the area of said aperture is left exposed beyond the edge of said sheet, as indicated by broken line 24, Fig. 1, said area being substantially equal to the area of bleed port 30 17, so that the air exhausted through said bleed port is replenished by the air supplied to the pneumatic through aperture 13. A deflection of the note sheet to the right, from any cause whatsoever, restricts the effective 35 area of aperture 13, and reduces the volume of air passing into the interior of pneumatic 15. The resulting collapse of the wall 20, due to the partial vacuum thus created in the pneumatic, effects, through the downward movement of depending arm 22, the movement of spool 4 to the left, against the resistance of spring 8, carrying the note sheet with it, so as to uncover more of aperture 13. On the other hand, should the note 40 sheet move too far to the left, uncovering more than the proper area of aperture 13,

the tendency of the wall 20 to collapse is entirely overcome. The spring 8 is thereby rendered operative to exert its expansive force in moving the shafts 6 and 10 and the 50 spool 4 to the left, carrying the note sheet in the direction to assume its proper registering position. The result of the responsive actions above set forth is to cause the spool 4 to be balanced in its longitudinal 55 position between the actions of the pneumatic 15 and spring 8, thereby securing a sensitive and quickly responsive automatic adjustment of said spool and its note sheet with respect to the apertures 12 and 13 of 60 the tracker-bar 5.

The above described device, it will be seen, secures at all times the correct and accurate positioning of the note sheet, with the provision of a minimum number of parts 65 over and above the parts already present in the existing types of automatic musical instruments. The spring 8, ordinarily employed for the centering and holding of the removable music spool, is rendered capable 70 of a new and independent function, namely, the coöperation with the pneumatic 15 in maintaining the note sheet in its proper registering position.

75 I claim,

In an automatic musical instrument, a pneumatic bellows mechanism, comprising a stationary wall and a movable wall, inclosing a chamber, an exhausting device for maintaining a tension in said chamber, 80 whereby to actuate said movable wall, one of said walls providing a restricted opening which connects said chamber with said exhausting device, said opening being surrounded by a recess of extended area, and 85 a sheet of foraminous material covering said recess and spaced from said opening.

Dated this fourth day of August, 1914.

THEODORE P. BROWN.
